ATTORNEY

UNITED STATES PATENT OFFICE.

THOMAS E. GRIFFITH, OF WINSTON-SALEM, NORTH CAROLINA.

GARMENT-SUPPORTER.

1,244,194.

Specification of Letters Patent. Patented Oct. 23, 1917.

Application filed January 29, 1916. Serial No. 75,152.

To all whom it may concern:

Be it known that I, THOMAS E. GRIFFITH, a citizen of the United States, residing at Winston-Salem, in the county of Forsyth 5 and State of North Carolina, have invented certain new and useful Improvements in Garment-Supporters, of which the following is a specification.

This invention relates to garment supporters and has for its primary object to provide a support for hosiery, stockings, trousers, underwear or the like and may be attached to a garter or suspenders.

A further object of this invention is the provision of a supporter that will clamp the hem of the garment and positively support it without danger of the garment being torn or damaged.

A further object of the invention is the provision of a supporter that may be easily attached to the garment and quickly detached therefrom.

A further object of this invention is the provision of a supporter which consists of 25 comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, wherein is illustrated the preferred form of my invention, in which;

Figure 1 is a perspective view of the garment support.

Fig. 2 is an edge elevation showing the supporter attached to the garment.

Fig. 3 is a vertical section.

The base plate 1 is provided which consists of a rectangular piece of metal having lugs 2 formed thereon at its free end, and which is bent upon itself at its opposite end 45 to form a double thickness of the plate by reason of the bent over portion 3 lying against the face of the plate 1 and extending downwardly thereon for a short distance. This member 3 is provided with a loop 4 which forms a hinge for the swinging clamp plate 5.

The clamp plate 5 is also provided with ears 6 which are identical with the ears 2 and which are adapted to engage with the 55 ears 2 when the clamp is closed.

Flanges 7 are provided along the longi-

tudinal edges of the clamp plate 5 and the ends of the flanges are provided with apertures for the reception of pivot pins 8. A pair of clips 9 are provided, one of which 60 is mounted upon the pin 8 for pivotal movement and a finger plate 10 is integrally connected to the clips 9 so that when the finger plate is swung toward or away from the clamp plate 5, the clips 9 will rotate upon 65 their pivots. A sliding ring 11 is provided which surrounds the base plate 1 and is large enough to freely slide up and down to lock the parts when the garment is clamped.

In the operation of the device, the garment is inserted between the base plate 1 and the swinging clamp plate 5 and these plates are brought together whereupon the finger plate 10 will be swung forwardly on 70 the pivot 8 to contact with the plate 5 and by this operation, the clips 9 will, at their ends 12, engage the garment, pressing it against the lugs 2 and thereby securely hold the garment. The ring 11 will then be 75 pushed down over the different members constituting the clamp and lock the parts together as shown by Fig. 2 of the drawing. To release the garment it is only necessary to push the ring 11 upwardly so that the 80 parts may be easily opened and the garment removed therefrom.

From the foregoing it will be observed that a very simple and durable supporter 90 has been provided, the details of which embody the preferred form. I desire it to be understood however, that slight changes or modifications in the minor details of construction may be made without departing 95 from the spirit of the invention or the scope 95 of the claims hereunto appended.

I claim:

1. A garment supporter comprising a clamp having a fixed and a movable member, a ring circumscribing the said members, a pair of clips pivotally mounted on the movable member, means associated with the said clips and adapted to be manually moved into engagement with the said movable member for moving the ends of the said 100 clips into engagement with the ends of the fixed member, the said ring being slidable on the said movable and fixed member for engaging the said means.

2. A garment supporter comprising a base plate, a hinge formed on the base plate, 110 a swinging clamp plate mounted for swing-

ing movement on said hinge, a finger plate to which is secured clips is pivoted to the swinging clamp plate and adapted to move the said clips into engagement with the said base plate, and a ring embracing the base plate and adapted to slide thereover and engage the finger plate to hold the latter in operative position.

3. A garment supporter comprising a base plate, a hinge formed at one end of the said base plate, lugs formed at the opposite end and projecting laterally from the edge of the base plate, a swinging clamp plate mounted on the hinge, the said swinging clamp plate also having lugs corresponding to the lugs on the base plate, clips pivotally mounted at opposite edges of the swinging clamp plate above the lugs on the said clamp plate, and means connected to the clips for moving the ends of the latter into engagement with the lugs on the base plate for tight engagement therewith to clamp the said base plate and the swinging clamp plate in close relation.
- 25 4. A garment supporter comprising a base plate, a hinge formed on said base plate, a

swinging clamp plate mounted for swinging movement on said hinge, flanges formed on each side of said swinging clamp plate, a plate pivotally mounted on said flanges and provided with clips adapted to engage the said base plate, and means for securing said means to said swinging clamp plate.

5. A garment supporter comprising a base plate, a hinge formed at one end of said base plate, lugs formed at the opposite end of said base plate, a swinging clamp plate mounted in said hinge to swing toward or away from said base plate, a finger plate having a pair of integral clips the said clips being pivotally connected to the said base plate, the said clips being adapted to have their ends engage the said lugs, and means for locking said finger plate to said swinging clamp plate.

In testimony whereof I affix my signature in presence of two witnesses.

THOMAS E. GRIFFITH.
